HYPODERMIC SYRINGE

Arthur E. Smith, Los Angeles, Calif.

Application December 6, 1947, Serial No. 790,044

6 Claims. (Cl. 128—218)

1

This invention relates to a hypodermic syringe. The general object of the invention is to provide an improved syringe by means of which various drugs may be readily and efficiently injected.

A more specific object of my invention is to provide a syringe of the disposable ampule type wherein a syringe barrel and a disposable ampule are employed and wherein the barrel and ampule have novel parts.

A more specific object of my invention is to provide a novel ampule syringe barrel and rear member.

Another object of the invention is to provide a novel ampule including novel stoppers.

A further object of the invention is to provide an ampule syringe including novel means for locking the syringe plunger to the piston cork of the ampule.

Other objects and advantages of the invention will be apparent from the following description taken in connection with the accompanying drawings, wherein:

Fig. 1 is a side elevation of an ampule employing the features of my invention;

Fig. 2 is a side elevation of the syringe;

Fig. 3 is a central, sectional view of the ampule inserted in the barrel and before the syringe has been placed in condition for use;

Fig. 4 is a view similar to Fig. 3, showing the syringe in use;

Fig. 5 is a central, sectional view, partly in elevation, showing the syringe after the medicinal preparation has been discharged;

Fig. 6 is a section taken on line 6—6; Fig. 4, and

Fig. 7 is a fragmentary, sectional view, showing a modification of my invention.

Referring to the drawing by reference characters, I have shown my invention as embodied in a syringe which is indicated generally at 10. As shown the syringe includes a barrel 11 which has a central bore 12 and an arcuate, finger-engaging flange 13 thereon. At the front end the barrel has a front member 14 secured thereon. This front member includes a forwardly directed tip portion 15 and has a frusto-conical recess 16 in it wherein which at its outer end has a substantially hemispherical seat 17. At its rear end the barrel has a collar 18 which may be soldered in place. This collar is internally threaded as at 19.

In the barrel I arrange an ampule centering and holding member 20. The member 20 includes a body 21, slideable within the barrel, and an integral, rearwardly directed sleeve 22. The sleeve 22 is cylindrical and at its outer end includes a threaded portion 23 which is adapted to thread

2

edly engage the threads 19 previously mentioned. The sleeve 22 is threaded at its extreme end 24 to receive threads 25 on a rear member 26 which includes a skirt 27, slideable over the rear end of the barrel.

The front end of the ampule engaging member is bevelled as at 30 and is adapted to engage and center the end 31 of an ampule 32 which contains a medicinal preparation to be injected. The diameter of the forward portion of the barrel 11 is slightly less than the diameter at 32 of the rear portion of the barrel in which the centering member 20 slides so that the shoulder 33 provided by the change in diameter affords a stop for the centering member.

The ampule includes a front cork 34 made of rubber and includes a body 35 adapted to be seated in the ampule, a shoulder 36 engaging the end of the ampule and a tapering, forwardly projecting tip 37 which has a hemispherical seat 38 at its forward end. The stopper 34 includes coaxial front and rear recesses 39 and 40, separated by a diaphragm 41. At the inner end of the ampule I arrange a piston stopper 45 which has peripheral beads 46 slidably engaging the interior of the ampule. The piston stopper is made of rubber and is provided with a rectangular slot 47 which opens rearwardly and at its inner end is closed and is provided with arcuate slots 30 48 which intersect the rectangular slot 47.

A plunger 50 is adapted to slide in the bore 51 of the centering member 20. This plunger has a thumb-engaging rear end 52 which may be threaded in place and at its front end has a shoulder 53 from which a stem 54 projects. The shoulder 53 engages the end of the piston stopper to push the latter. The stem has a transverse bar 55 mounted thereon which is preferably rectangular and is substantially the same size as the rectangular slot 47. The front end of the centering member includes a recess 56 in which the shoulder 53 is seated.

On the ampule I arrange a needle which includes a front portion 60, a rear portion 61 and a hemispherical intermediate portion 62. The barrel includes a large ampule introduction slot 65 and a smaller slot 66 which may be used to assist in the removal of the ampule. A protection cap 67 engages the tip 37 of the ampule to maintain the needle sterile.

In use the plunger is fully withdrawn and the ampule, in the condition shown in Fig. 3, is inserted through the slot 65 to assume the position shown. The needle passes through a hole 60' in

the tip 15 in Fig. 3 with the pointed end of the needle not piercing the diaphragm 35.

The operator then pushes the rear member 26 forwardly until the threads 23 engage the threads 19, whereupon the rear member is rotated, causing the threads to engage and moving the centering member against the ampule, thus centering the ampule and pushing it forwardly in the barrel so that it assumes the position shown in Fig. 4, causing the needle to pierce the diaphragm 41. The operator then pushes the plunger forward, causing the cross member 55 on the plunger to enter the slot 47. The plunger is then advanced in the slot until it reaches the inner end thereof, whereupon the plunger is rotated, thus causing the cross member 55 to enter the arcuate slot 48 to thereby lock the parts together. The syringe is now ready for use.

After the needle has been inserted in the patient, the plunger may be advanced slightly and then withdrawn. If blood appears in the ampule the needle is in a blood vessel and should be withdrawn and a fresh insertion made.

In Fig. 7 I show a modification of my invention wherein parts similar to those previously described are designated by single primed reference numerals. In the modification the inner end 74 of the needle is in the form of a tube and instead of the recess 40 I provide an outer recess 70 and an inner recess 71. A sealing disc 72 is seated in the recess 70, and in the recess 71 I place a medicinal tablet 73. The vehicle for the tablet 73 is contained in the ampule. In use the ampule is inserted in the bore 12' of the barrel and when pushed forward, as described above, the inner end of the portion 74 will pierce the diaphragm 41' and will dislodge the disc 72, causing the tablet 73 to be placed in the liquid in the ampule, whereupon the tablet will be dissolved to provide a fresh solution.

From the foregoing description it will be apparent that I have invented a novel hypodermic syringe which can be economically manufactured and which is highly efficient for its intended use.

Having thus described my invention, I claim:

1. A syringe including a barrel and an ampule, said syringe including a front member having a hole therethrough, an ampule holding member slidable within the barrel, said holding member including an externally threaded portion, said barrel having an internally threaded portion at the rear end thereof, said holding member being slidable in said threaded portion, said threads being engageable, a plunger slidable within said holding member, said ampule having a front member thereon, said front member having an axial bore and having a diaphragm closing the inner end of said bore, a needle in said bore, said needle being shiftable to pierce the diaphragm, a piston stopper in the rear end of said ampule, and means to releasably connect the stopper to the plunger.

2. A syringe including a barrel and an ampule, said syringe including a front member having a hole therethrough, a rear member slidable on said barrel, a tubular ampule holding member mounted on said rear member, said holding member including an externally threaded portion, said barrel having a collar at the rear end thereof, said holding member being slidable in said collar, said collar being internally threaded to engage the threads on said holding member, a plunger slidable within said holding member, an ampule in said barrel, said ampule having a

front member thereon, said front member having an axial bore and having a diaphragm closing the inner end of said bore, a needle in said bore, said needle being shiftable to pierce the diaphragm, and a piston stopper in the rear end of said ampule, and connecting means on the inner end portion of the plunger and the piston stopper to releasably lock the plunger to the stopper.

3. A syringe including a barrel and an ampule, said syringe including a front member having a hole therethrough, a rear member being slidable on said barrel, a tubular ampule holding member on said rear member, said holding member including an externally threaded portion, said barrel having a collar at the rear end thereof, said holding member being slidable in said collar, said collar being internally threaded to engage the threads on said holding member, a plunger slidable within said holding member, said plunger having a shoulder on the inner portion thereof and having a stem projecting forwardly from said shoulder, a transverse bar on said stem, an ampule in said barrel, said ampule having a front member thereon, said front member having a bore and having a diaphragm closing the inner end of said bore, a needle in said bore, said needle being shiftable to pierce the diaphragm, and a piston stopper in the rear end of said ampule, said stopper having a rectangular slot extending inwardly from the rear end thereof, said piston stopper having arcuate slots intersecting the rectangular slot, said transverse bar being of a size to first enter said rectangular slot and upon rotation to enter said arcuate slots, said shoulder on the plunger being adapted to engage and push the end of the piston stopper when the transverse bar is in the arcuate recesses.

4. A syringe including a barrel, said syringe barrel including a front member having a hole therethrough and having a substantially hemispherical recessed portion adjacent to said hole, a rear member slidable on said barrel, an ampule centering and holding member mounted on said rear member, said centering and holding member having a bevelled front face, said barrel having a shoulder limiting the inward movement of said centering and holding member, said centering and holding member including an integral sleeve having an externally threaded portion thereon, said barrel having a collar at the rear end thereof, said sleeve being slidable in said collar, said collar being internally threaded to engage the threads on said sleeve, a plunger slid able within said sleeve, said plunger having a shoulder on the inner portion thereof and having a stem projecting forwardly from said shoulder, and a transverse bar on said stem.

5. A syringe including a barrel and an ampule, said barrel including a front member having a hole therethrough, a rear member slidable on said barrel, an ampule holding member on said rear member, said holding member including an integral sleeve having an externally threaded portion thereon, said barrel having a collar at the rear end thereof, said sleeve being slidable in said collar, said collar being internally threaded to engage the threads on said sleeve, a plunger slid able within said sleeve, said plunger having a shoulder on the inner portion thereof and having a stem projecting forwardly from said shoulder, a transverse bar on said stem, an ampule in said barrel, said ampule having a front member thereon, said front member having an axial bore and having a diaphragm closing the inner

end of said bore, a needle in said bore, said needle having a protuberance thereon, said needle being shiftable to pierce the diaphragm, and a piston stopper in the rear end of said ampule, said stopper having a rectangular slot extending inwardly from the rear end thereof, said piston stopper having arcuate slots intersecting the rectangular slot, said transverse bar being of a size to first enter said rectangular slot and upon rotation to enter said arcuate slots, said shoulder on the plunger being adapted to engage and push the end of the piston stopper when the transverse bar is in the arcuate recesses.

6. A syringe including a barrel and an ampule, said syringe barrel including a front member having a hole therethrough and having a substantially hemispherical recessed portion adjacent to said hole, a rear member slideable on said barrel, an ampule centering and holding member mounted on said rear member, said centering and holding member having a bevelled front face, said barrel having a shoulder limiting the inward movement of said centering and holding member, said centering and holding member including an integral sleeve having an externally threaded portion thereon, said barrel having a collar at the rear end thereof, said sleeve being slideable in said collar, said collar being internally threaded to engage the threads on said sleeve, a plunger slideable within said sleeve, said plunger having a shoulder on the inner portion thereof and having a stem projecting forwardly from said shoulder, a transverse bar on said stem, said barrel having

an ampule receiving slot, an ampule in said barrel, said ampule having a front member thereon, said front member having an axial bore and having a diaphragm closing the inner end of said bore, a needle in said bore, said needle having a protuberance thereon engaging in said substantially hemispherical recess, said needle being shiftable to pierce the diaphragm, and a piston stopper in the rear end of said ampule, said stopper having a rectangular slot extending inwardly from the rear end thereof, said piston stopper having arcuate slots intersecting the rectangular slot, said transverse bar being of a size to first enter said rectangular slot and thereafter upon rotation to enter said arcuate slots, said shoulder on the plunger being adapted to engage and push the end of the piston stopper when the transverse bar is in the arcuate recesses.
